J. J. COOK.

FISH BASKET OR CREEL SUPPORTING HARNESS.

APPLICATION FILED DEC. 6, 1918.

1,302,312.

Patented Apr. 29, 1919.

UNITED STATES PATENT OFFICE.

JAY J. COOK, OF IRON RIVER, MICHIGAN.

FISH-BASKET OR CREEL SUPPORTING HARNESS.

1,302,312.

Specification of Letters Patent.

Patented Apr. 29, 1919.

Application filed December 6, 1918. Serial No. 265,565.

To all whom it may concern:

Be it known that I, JAY J. COOK, a citizen of the United States, residing at Iron River, in the county of Iron and State of Michigan, have invented certain new and useful Improvements in Fish-Basket or Creel Supporting Harness, of which the following is a specification.

The present invention comprehends generally improvements in that class of invention known as package and article carriers and more particularly relates to a fish basket or creel supporting harness.

It is the primary aim and object of this invention to provide a device of the above mentioned character designed so that the creel or fish basket will be suspended from the left shoulder leaving the right arm of the fisherman free for casting and manipulating the rod while the creel is also held against the body, a distinct advantage when the fisherman is wading a swift stream or passing through underbrush.

As an additional and equally important object this invention consists in the provision of a supporting harness of the character mentioned of improved construction and designed to receive and support the creel without being attached directly to the creel, being incidentally positioned to brace and reinforce the bottom of the creel and thereby increase the longevity thereof, and in addition the component parts are adjustable so that the harness will accommodate various sizes of the conventional style of creel and at the same time be effectively applied on the body of the fisherman.

Among the other aims and objects of the present invention may be recited the provision of a device of the above mentioned character wherein the number of parts are comparatively few, the construction simple, the cost of production low and the efficiency high.

The improvements in the details and arrangement of parts will be apparent from an inspection of the accompanying drawings, in connection with the specific description hereinafter contained, and wherein the preferred embodiment of the invention is disclosed for the purpose of imparting a full understanding of the invention.

The invention is clearly illustrated in the accompanying drawings, in which:

Figure 1 is a perspective view of the har-

ness detached but showing a creel arranged therein, and

Fig. 2 is a front elevation showing the device applied.

Similar characters of reference are employed in all of the above described views, to indicate corresponding parts.

Referring now, more particularly, to the accompanying drawings there is provided a relatively wide shoulder engaging strap 1 65 the terminals of which have connected thereto flexible loops 2 for loosely supporting metal rings 3 designed to be positioned against the chest and the back of a fisherman near the left shoulder and connected to 70 each other by the body engaging strap generally designated by the numeral 4 which body engaging strap preferably consists of a main section 5, the inner end of which is desirably detachably connected to the adjacent ring 3 75 by means of a snap hook 6 while the terminal portion is formed with openings 7 for coacting with the buckle 8 carried by the outer end of the other section 9 of the body engaging strap, and which latter section is in 80 turn loosely connected with the other metal ring as at 10. This body engaging strap is designed to be passed about the body and beneath the right shoulder for coacting with the shoulder strap 1 in supporting the harness in its entirety and leaving the right arm of the fisherman free for casting and manipulating the rod (not shown).

With a view toward providing the improved receiver, there is employed a pair 90 of substantially vertically disposed sectional straps generally designated by the numeral 11, the inner short sections 12 of which have their inner ends loosely connected in the respective rings 3 while buckles 13 are fitted on the outer ends thereof and are designed to adjustably engage any of the openings in the inner terminal portions of the main section 14. The major portions of the main section 14 are arranged in a U-shaped form including the intermediate portions 15 and the spaced side portions 16. Upper and lower straps 17 are now provided and arranged in a substantially rectangular form having the side portions connected to the opposing side 105 portions of the main sections 14 preferably near the upper and lower ends of the said side portions 16 by means of fastening devices 18 and these straps 17 preferably have their adjacent terminal ends respectively 110

fitted with buckles 19 and provided with a series of openings 20 for coacting with the buckles 19 in fastening the straps horizontally about the side walls of a creel 21 of a conventional type. It is to be noted that the side portions 16 of the major portion of the sections 14 are arranged vertically and on opposite sides of the side walls of the creel 21 while the intermediate portions 15 extend transversely across the bottom of the creel to brace and reinforce the bottom of the creel and thereby increase the longevity thereof. By the provision of the buckles 19 the straps 17 are capable of adjustment to accommodate various sizes of a conventional type creel. Also, by the provision of the buckle 13 the creel may be supported in a properly adjusted position on the side of the body of the fisherman beneath the left arm and will be held against the body of the fisherman by the improved arrangement of harness so as not to interfere with the convenience of the fisherman when wading a swift stream or passing through underbrush. It is believed in view of the foregoing description that a further detailed description of the operation of the invention is entirely unnecessary. Likewise, it is believed that the operation of the invention may be readily apparent. Still further embodiments than those herein especially defined may be resorted to as conditions or preference may dictate, as may be in keeping with the hereto appended claim.

Having thus fully described the invention what is claimed as new and desired to be secured by Letters Patent, is:

A creel supporting harness including a shoulder engaging strap, rings connected to the ends thereof, a body engaging strap connected with the rings, a receiver composed of a pair of sectional straps, each of the sectional straps including inner and main sections, the inner sections of the sectional straps being connected with the rings, the main sections being adjustably connected to the inner sections and arranged in a U-shaped form embodying an intermediate portion and spaced side portions, and upper and lower straps arranged in rectangular form and having their side portions connected with the side portions of the main sections and having their adjacent terminal ends adjustably connected with each other.

In testimony whereof, I affix my signature hereto.

JAY J. COOK.
